MECHANICAL PENCIL

Max Schaefer, Bloomfield, N. J., assignor to
Eagle Pencil Company, a corporation of Dela-
ware

Application February 8, 1937, Serial No. 124,530

4 Claims. (Cl. 120—18)

My present invention relates to mechanical pencils, more particularly of the helical feed type.

As conducive to a clear understanding of the invention, it is noted that the construction would be rendered mechanically weak and subject to distortion and jamming if the feed tube were in the form of helically wound metal ribbon or the like, rotatable relative to the casing but of the low pitch feasible in constructions in which the feed tube is rigid with the casing. If for the purpose of attaining adequate mechanical strength the feed tube ribbon is however made of a higher pitch, it would be subject to rotary slippage under writing pressure, with consequent retraction of the lead.

It is among the objects of the invention to provide a pencil of the type presenting a high pitch rotatable helical feed tube, which pencil is adjustable for writing, without the looseness or slippage that leads to lead recession under writing pressure, and this without appreciably adding to the cost of the pencil, either for materials or for precision of manufacture.

Another object is to provide a pencil of the above type, presenting the above advantages, without the need for modification of any of the conventional elements or of the mode of assembly thereof, but by the simple expedient of adding to the structure an element of negligible cost assembled into the structure with great ease.

In the accompanying drawing in which are shown one or more of various possible embodiments of the several features of the invention:

Fig. 1 is a view in longitudinal cross-section of one embodiment of the invention,

Fig. 2 is a sectional view on a greatly enlarged scale taken on line 2—2 of Fig. 1,

Fig. 3 is a perspective view of a preferred embodiment of brake element, and

Fig. 4 is a view similar to Fig. 2 of a slight modification.

Referring to the drawing, the casing shown as a metal tube 10 has a ferrule 11 at its tapered point into which there is axially fitted and secured against movement the lead tube 12, longitudinally slotted at 13. Telescoped into the opposite end of the casing 10 is a tube 14 which is frictionally held therein for facility of rotation thereof, accomplished preferably by means of the conventional eraser ferrule 15 tightly fitted thereover by friction. The tube 14 has a reduced extension 16 rigidly fixed, as for instance, by indentations 17, to the feed tube 18, which is accordingly rotatable about the lead tube 12 upon turning of the eraser ferrule 15. The feed tube 18 is

illustratively shown as formed from an elongated strip of sheet metal, helically wound on a relatively high pitch, illustratively of three to four convolutions per inch. The ribbon is preferably crowned as at 19 to present a convex outer surface.

The feed tube 18 is connected with the lead tube 12 for propulsion of the lead in any conventional manner. Preferably the propelling unit is a lead clutch tube 20 lodged within the lead tube 12. It clasps the rear end of the lead 21 and has a lateral wing or extension 22 which protrudes outward from the slot 13 into the helical feed track 23 of the feed tube. There is also illustratively shown a conventional expelling mechanism comprising a pin 24, within the lead clutch tube 20, equipped with a lateral offset 25, also protruding through the slot 13 into the track 23 and trailing the wing 22 by one or more convolutions.

The relatively high pitch of helical track set forth, made necessary for mechanical strength, may be less than the critical angle of friction, so that rotary slippage of the feed tube is apt to occur under ordinary writing pressure. Brake or snubber means is provided according to the invention to retain the feed tube against such slippage. This means is enclosed in the casing and exerts resilient pressure on the feed tube to impose a load on the latter for the purpose set forth, without however interfering with rotation thereof from the eraser ferrule 15 in effecting the desired lead feed.

In a preferred specific embodiment, the brake member comprises a spring-brass clasp 26, made of a unitary blank longitudinally folded along line 27 to form a pair of sides or jaws 28 and 29, each of which is symmetrically curved substantially like a pair of calipers, convex at the outside and concave at the inside. This clasp member is simply placed in straddling relation over any part of the length of the feed tube 18 and introduced therewith in the assembly of the pencil into the casing 10 thereof. As best shown in Fig. 2 and especially with a metal pencil casing of polygonal cross-section, illustratively shown in Fig. 2 as hexagonal, the hinge line 27 of the clasp naturally lodges itself in one of the dihedral angles 30 of the casing and the length of each jaw is such that the free edges 31 and 32 thereof are cammed toward each other by the sides 33 and 34 respectively of the casing determining the dihedral angle whose vertex is the edge 35 diametrically opposite edge 30, thereby causing the bowed sides

of the clasp to embrace the feed tube with substantial resilient pressure.

The brake member set forth is of substantially negligible cost and entails no difficulty in assembly or introduction into the pencil. It exerts sufficient frictional load upon the feed tube to prevent undesired rotation of the latter under writing pressure. Yet the load imposed by the brake is not so great as to cause slippage of the eraser ferrule 15 in lead propelling or retracting operation. The added load due to the brake clasp 26 also renders the operation of propelling and retracting smoother and more uniform and enhances the comfort of adjusting the pencil.

The helical feed tube extending substantially the length of the pencil when the pencil is charged with a long lead, the lead propelling clutch tube with its wings or lateral offsets 22 and 25 is near the eraser end of the pencil above the extension 16 that encircles the feed tube and well above the brake member 26. Yet in the use of the pencil, as the lead is consumed and the propelling tube is moved downward to reach and traverse the length of the brake member, there is no interference or jamming of the wings 22 and 25 with respect to the brake member. From one aspect this is due to the fact that the brake member engages only the crowned face, below which the ends of the wings 22 and 25 are lodged, so that the latter cannot touch the brake even though the concavities of the jaws 28 and 29 thereof should extend directly over the slot of the lead tube 12.

From another aspect the wings 22, 25 will clear the brake member in the operation of the feed tube by reason of the fact that these wings move in longitudinal slot 13 of the lead tube 12 which as shown in Fig. 1 is substantially in registry with the gap between jaw edges 31 and 32 of the brake. The latter being fixed against rotary displacement, the wings could not reach and engage the feed tube clasping portions of the brake member, even if the feed tube were not crowned in the manner preferred.

The crowned surface of the feed tube 18 provides a smooth surface which rides in the brake member 26, while the relatively sharp edges 31 and 32 of the latter are retained by the casing against slippage. Accordingly, the brake member is retained against rotation within the casing and the rotary movement during lead feed or retraction is entirely between the rotating feed tube and the fixed brake member.

It is seen that the brake member may directly engage the helical feed tube at any portion between the ends thereof and incidentally serves also to steady the latter against shifting or distortion.

The use of the brake in the construction set forth thus in no-wise interferes with the preferred application of the invention to a mechanical pencil with a long lead, that is, with one substantially the length of the pencil. Moreover the construction is less expensive than one in which some special structure beyond the helical feed tube is needed to accommodate.

The embodiment of Fig. 4 shows a pencil casing 10' circular in cross-section in which the brake clasp 26' is frictionally engaged about the feed tube 18' in much the same way as in Fig. 2, the curvature of the casing contributing to the

camming action of approach of the jaws upon the ends 31', 32' thereof, with resultant resilient clasping of the feed tube.

It will thus be seen that there is herein described apparatus in which the several features of this invention are embodied, and which apparatus in its action attains the various objects of the invention and is well suited to meet the requirements of practical use.

As many changes could be made in the above 10 construction, and many apparently widely different embodiments of this invention could be made without departing from the scope thereof, it is intended that all matter contained in the above description or shown in the accompanying drawing 15 shall be interpreted as illustrative and not in a limiting sense.

Having thus described my invention, what I claim as new and desire to secure by Letters Patent is:

1. A mechanical lead pencil comprising a casing, a helical feed tube rotatably mounted therein and extending substantially the length thereof and having a relatively steep feed track therealong, lead propulsion means in said lead tube 25 having wing means protruding into the slot thereof, said feed tube being crowned along the entire length thereof and a brake clutch member embracing said feed tube at an intermediate portion of the length thereof and engaging said casing, whereby in operation the wing means riding in said track will move toward and along the length of said brake member free from conflict therewith.

2. A mechanical pencil comprising a casing, a feed tube therein presenting a helical feed track extending substantially the length of the pencil and having associated means at the rear end for rotating the same within the casing, a lead tube rigid with the casing and within said feed tube 40 having a longitudinal slot, lead propeller means within said lead tube having wing structure extending through said slot into said helical feed track, a brake clutch member, embracing said feed tube at an intermediate part of the length 45 thereof and also engaging the inner wall of said casing, said clutch being free from the path of movement of said propeller wings in the operation of the pencil.

3. The combination recited in claim 2 in which 50 the brake member is of sheet metal with jaws concave at their inner faces embracing the feed tube and with the hinge end as well as the free edges of said brake member in engagement with the inner wall of the casing, each jaw being of 55 length such as to cause the jaws to be urged inward toward each other by the concavity of the inner casing wall for frictionally clasping the tube embraced thereby.

4. The combination recited in claim 2 in which 60 the casing is polygonal in cross-section and the sheet metal brake member has its hinged portion lodged in one of the edges of the casing and the free edges thereof respectively engaging the sides of the dihedral edge whose vertex is the opposite 65 edge of the casing, each jaw being of length such as to cause the jaws to be urged inward toward each other by the concavity of the casing, thereby by frictionally to clasp the tube embraced thereby, to preclude slippage.

MAX SCHAEFER.
